[57] ABSTRACT

Selecting pulse signals for selecting recording positions are combined with input information such as picture signals to produce the recording signals representing not only the optical density of recording but the recording positions, and the recording signals are converted into the driving signals which are applied to selected input terminals of a transformer assembly so that across the series-connected secondary windings corresponding to the recording position indicated by the selecting pulse signal there is induced the electrostatic recording voltage. The recording voltages are applied to recording electrodes or styluses to form an electrostatic latent image of said input information upon a recording medium. The latent image is developed and fixed to provide a permanent recording.

ELECTROSTATIC RECORDING APPARATUS WITH CORE MATRIX

BACKGROUND OF THE INVENTION

The present invention relates to generally an electrostatic recording apparatus and more particularly a high-speed electrostatic recording apparatus of the type recording input information with the electrostatic recording voltages induced and applied to recording electrodes or styluses selected by recording position selecting pulses.

In general, the recording speed of most of recording apparatus for recording information transmitted by a data transmission line or processed by an electronic computer is very low as compared with the data transmission line or data processing speed so that a high-speed recording apparatus has been demanded. Furthermore a recording apparatus which produces less or no recording noise has been demanded. Therefore, research and development of various non-impact recording systems such as electrostatic recording systems, electrophotographic recording systems, silver halide recording systems, heat-sensitive recording systems, dry silver recording systems, ink jet recording systems and so on have been carried out. Of these non-impact recording systems, the electrostatic recording systems are most advantageous because the recording speed is high, the recorded images have good qualities, the power consumption is less and the apparatus itself is simple in mechanism. The electrostatic recording systems have been widely used in the fields of dot matrix electrostatic printers, plotters, facsimile systems and so on. In view of economy and recording density however, the conventional electrostatic recording apparatus has not been satisfactory mainly because of the problem of distributing the electrostatic recording voltages among recording electrodes or styluses. One typical example of the conventional electrostatic recording apparatus generally comprises an AND gate circuit, amplifiers, transformers and a recording electrode or stylus head. A plurality of AND gates are sequentially opened to pass the picture signals to the amplifiers, and the outputs of the amplifiers are applied to a primary winding of a pulse transformer so that a high voltage may be induced across the secondary winding thereof and supplied to a multistylus electrode. An electrostatic latent image is formed upon a recording medium in contact with the multistylus electrode, and developed and fixed to produce the permanent recording. The multistylus electrode of the electrostatic apparatus of the type described has 1,275 styluses with a stylus density of 150 styluses per inch in order to reproduce or record a satisfactory image upon a recording medium with the width of 8½ inches so that 1,275 amplifiers and 1,275 pulse transformers are required. As a result, the conventional electrostatic recording apparatus of the type described is extremely large in size and very expensive.

SUMMARY OF THE INVENTION

In view of the above, the primary object of the present invention is to provide a high-speed electrostatic recording apparatus based upon the novel electrostatic recording voltage distribution method so that printing or recording with a high recording density can be accomplished at such a high speed as compatible with the data transmission speed or data processing speed.

Another object of the present invention is to reduce the numbers of amplifiers and pulse transformers based upon the novel electrostatic recording voltage distribution method so that an electrostatic recording apparatus which is compact in size, light in weight and inexpensive to manufacture may be provided.

5 A further object of the present invention is to provide an electrostatic recording apparatus capable of high-speed recording with a high recording density based upon the novel electrostatic recording voltage distribution method.

10 15 The above and other objects, features and advantages of the present invention will become more apparent from the following description of the preferred embodiments thereof taken in conjunction with the accompanying drawing.

BRIEF DESCRIPTION OF THE DRAWING:

FIG. 1 (consisting of FIGS 1A and 1B) is a block diagram of a first embodiment of the present invention;

20 FIG. 2 is a simplified diagram illustrating the relation between the primary windings and the secondary windings of a transformer assembly of the first embodiment shown in FIG. 1;

25 FIG. 3 is a graph illustrating the electrostatic recording voltage vs. optical density of recording characteristic curves of a recording medium;

30 FIG. 4 is a simplified diagram illustrating the arrangement of the primary and secondary windings of a transformer assembly of the type which can respond to the unipolar input;

35 FIG. 5 (consisting of FIGS 5A and 5B) is a block diagram of a second embodiment of the present invention;

FIG. 6 shows diagrammatically the arrangement of 40 the transformer assembly of the type in which the output terminals are selected one by one;

45 FIG. 7 (consisting of FIGS 7A and 7B) is a block diagram of a sixth embodiment of the present invention of the type in which the electrostatic recording voltages are simultaneously applied to a plurality of recording styluses;

FIGS. 8-10 show diagrammatically the arrangements 50 of the transformer assemblies of the type capable of simultaneously outputting the electrostatic recording voltages from a plurality of output terminals thereof;

FIGS. 11-15 are cross sectional views of bobbins of the transformer assemblies illustrating the arrangements of the secondary windings in accordance with the present invention; and

55 FIG. 16 is a diagram of a fourteenth embodiment of the present invention.

DESCRIPTION OF THE PREFERRED EMBODIMENTS:

First Embodiment

Referring to FIG. 1 illustrating diagrammatically an electrostatic recording apparatus in accordance with the present invention, a picture signal is applied to a picture signal input terminal 11. The output signals of a selecting pulse generator 12 are applied to a gate circuit 13, and the signals which pass through the gate circuit 13 are amplified by a driver 14 and applied to primaries H_1-H_6 of a transformer assembly 15 through terminals E_1-E_6 .

60 65 In the transformer assembly 15, secondaries $L_{101}-L_{116}$ are wound on a core T_1 in the same direction as that of the primary H_1 . Secondaries $L_{201}-L_{208}$ are wound on a

core T_2 in a direction the same that of the primary H_2 whereas the secondaries L_{209} - L_{216} , are in the opposite direction. On a core T_3 are wound secondaries L_{301} - L_{304} and L_{309} - L_{312} in a direction the same as that of the primary H_3 whereas secondaries L_{305} - L_{308} and L_{313} - L_{316} , are in the opposite direction. On a core T_4 are wound secondaries L_{401} , L_{402} , L_{405} , L_{406} , L_{409} , L_{410} , L_{413} and L_{414} in a direction the same as that of the primary H_4 whereas secondaries L_{403} , L_{404} , L_{407} , L_{408} , L_{411} , L_{412} , L_{415} and L_{416} , are in the opposite direction. On a core T_5 are wound secondaries L_{501} , L_{503} , L_{505} , L_{507} , L_{508} , L_{511} , L_{513} and L_{515} in a direction the same as that of the primary H_5 whereas secondaries L_{502} , L_{504} , L_{506} , L_{508} , L_{510} , L_{512} , L_{514} and L_{516} , are in the opposite direction. On a core T_6 are wound secondaries L_{601} , L_{604} , L_{606} , L_{607} , L_{610} , L_{611} , L_{613} and L_{616} in the direction the same as that of the primary H_6 whereas secondaries L_{602} , L_{603} , L_{605} , L_{608} , L_{609} , L_{612} , L_{614} , and L_{615} , are in the opposite direction.

The same voltage V_1 is impressed across the primary windings H_1 - H_6 , and the secondary voltages having the same absolute value are induced across the secondaries, but the voltages $+V_2$ induced across the secondaries wound in the direction the same as that of the primaries H_1 - H_6 have the same polarity as that of the voltages impressed across the primaries whereas the voltages $-V_2$ induced across the secondaries wound in the opposite direction with that of the primaries have the opposite polarity.

One end of the secondary L_{101} is connected to a terminal F_1 whereas the other end, to the secondary L_{201} which in turn is connected in series to the secondaries L_{301} , L_{401} , L_{501} and L_{601} which are connected in series. The other end of the secondary L_{601} is grounded. These six secondary windings on the six cores connected in series comprise a selecting line of the terminal F_1 . The secondaries L_{102} , L_{202} , L_{302} , L_{402} , L_{502} and L_{602} are connected in series and one end of the secondary L_{102} is connected to a terminal F_2 whereas the secondary L_{602} is grounded. In like manner, the secondaries L_{103} - L_{603} , L_{104} - L_{604} , L_{105} - L_{605} , L_{106} - L_{606} , L_{107} - L_{607} , L_{108} - L_{608} , L_{109} - L_{609} , L_{110} - L_{610} , L_{111} - L_{611} , L_{112} - L_{612} , L_{113} - L_{613} , L_{114} - L_{614} , L_{115} - L_{615} and L_{116} - L_{616} are all connected in series, respectively, and the secondaries L_{103} - L_{116} are connected to terminals F_3 - F_{16} , respectively, whereas the secondaries L_{603} - L_{616} are grounded. The terminals F_1 - F_{16} are connected to styluses of a multistylus electrode **16**, respectively.

When the voltages are applied to the multistylus electrode **16**, the electrostatic latent images are formed upon a recording medium **17**. The latent images are developed and fixed to provide the permanent recording. Alternatively, the latent images may be developed upon the recording medium and then transferred upon a recording paper. In this case the recording medium may be used repetitively. Furthermore, the latent im-

ages upon the recording medium may be transferred onto a dielectric sheet and then developed and fixed to provide the permanent recording so that the recording medium may be also repetitively used.

In order to clearly show the relation between the polarity of the voltages induced across the secondaries and the directions of the secondaries, a winding matrix shown in Table 1 is utilized.

	F_1	F_2	F_3	F_4	F_5	F_6	F_7	F_8	F_9	F_{10}	F_{11}	F_{12}	F_{13}	F_{14}	F_{15}	F_{16}

mary H_4 whereas secondaries L_{403} , L_{404} , L_{407} , L_{408} , L_{411} , L_{412} , L_{415} and L_{416} , are in the opposite direction. On a core T_5 are wound secondaries L_{501} , L_{503} , L_{505} , L_{507} , L_{508} , L_{511} , L_{513} and L_{515} in a direction the same as that of the primary H_5 whereas secondaries L_{502} , L_{504} , L_{506} , L_{508} , L_{510} , L_{512} , L_{514} and L_{516} , are in the opposite direction. On a core T_6 are wound secondaries L_{601} , L_{604} , L_{606} , L_{607} , L_{610} , L_{611} , L_{613} and L_{616} in the direction the same as that of the primary H_6 whereas secondaries L_{602} , L_{603} , L_{605} , L_{608} , L_{609} , L_{612} , L_{614} , and L_{615} , are in the opposite direction.

The same voltage V_1 is impressed across the primary windings H_1 - H_6 , and the secondary voltages having the same absolute value are induced across the secondaries, but the voltages $+V_2$ induced across the secondaries wound in the direction the same as that of the primaries H_1 - H_6 have the same polarity as that of the voltages impressed across the primaries whereas the voltages $-V_2$ induced across the secondaries wound in the opposite direction with that of the primaries have the opposite polarity.

One end of the secondary L_{101} is connected to a terminal F_1 whereas the other end, to the secondary L_{201} which in turn is connected in series to the secondaries L_{301} , L_{401} , L_{501} and L_{601} which are connected in series. The other end of the secondary L_{601} is grounded. These six secondary windings on the six cores connected in series comprise a selecting line of the terminal F_1 . The secondaries L_{102} , L_{202} , L_{302} , L_{402} , L_{502} and L_{602} are connected in series and one end of the secondary L_{102} is connected to a terminal F_2 whereas the secondary L_{602} is grounded. In like manner, the secondaries L_{103} - L_{603} , L_{104} - L_{604} , L_{105} - L_{605} , L_{106} - L_{606} , L_{107} - L_{607} , L_{108} - L_{608} , L_{109} - L_{609} , L_{110} - L_{610} , L_{111} - L_{611} , L_{112} - L_{612} , L_{113} - L_{613} , L_{114} - L_{614} , L_{115} - L_{615} and L_{116} - L_{616} are all connected in series, respectively, and the secondaries L_{103} - L_{116} are connected to terminals F_3 - F_{16} , respectively, whereas the secondaries L_{603} - L_{616} are grounded. The terminals F_1 - F_{16} are connected to styluses of a multistylus electrode **16**, respectively.

When the voltages are applied to the multistylus electrode **16**, the electrostatic latent images are formed upon a recording medium **17**. The latent images are developed and fixed to provide the permanent recording. Alternatively, the latent images may be developed upon the recording medium and then transferred upon a recording paper. In this case the recording medium may be used repetitively. Furthermore, the latent im-

ages $+1 = +V_2$ and $-1 = -V_2$.

In the winding matrix, each column corresponds to each selecting line. When the driving voltage pulses of $+V_1$ are simultaneously impressed to the input terminals E_1 - E_6 , the voltages V_2 with the polarities depending upon the direction of the secondaries are induced across the secondaries L_{101} - L_{616} , respectively. As a result the voltage at the output terminal F_1 is the sum of the voltages induced across the secondaries L_{101} , L_{201} , L_{301} , L_{401} , L_{501} and L_{601} , that is $+6V_2$, but the voltages at the output terminals F_2 - F_{16} become $+2V_2$, $+2V_2$, $+2V_2$, $+2V_2$, $+2V_2$, $+2V_2$, $+2V_2$, $+2V_2$, $+2V_2$, $+2V_2$, $+2V_2$, $+2V_2$ and $-2V_2$, respectively. The relatively high voltage $+6V_2$ at the output terminal F_1 will be referred to as "the selected output voltage" whereas the relatively small voltages $\pm 2V_2$ at the output terminals F_2 - F_{16} , as "the spurious output" hereinafter in this specification. When the driving voltages $+V_1$, $+V_1$, $+V_1$, $+V_1$, $-V_1$ and $-V_1$ (which correspond the elements of the second column of the winding matrix, Table 1) are applied to the input terminals F_1 - F_6 , respectively, the selected output of $+6V_2$ appears at the output terminal F_2 . In like manner, when the drive voltage pulses corresponding to the elements of a selected column of the winding matrix are applied to the input terminals E_1 - E_6 , the selected output $+6V_2$ appears at a corresponding or selected output terminal, whereas the spurious output voltages appear at the other output terminals. The ratio of the absolute value of the spurious output ($-2V_2$ or $+2V_2$) to that of the selected output is called the selecting ratio which is one-third in the instant embodiment.

The transformer assembly **15** is illustrated in a simplified form in FIG. 2. The secondaries across which are induced the secondary voltages with the same polarity with that of the primary voltage are indicated by opened windings whereas the secondary windings across which are induced the secondary voltages with the polarity opposite to that of the primary voltage are indicated by twisted or closed windings. The winding matrix of the transformer assembly may be obtained from the (n,k) error-correcting code. For example from Golay code is obtained a winding matrix with 24 inputs, 2048 outputs and a selecting ratio of one-third.

FIG. 3 shows the relation between the electrostatic recording voltage applied recording styluses and the optical density of an image recorded upon a recording medium. In general, this relation changes depending upon the size of a recording stylus, the type of a record-

ing medium, and the polarity of recording voltage, but the relation may be generally depicted as shown in FIG. 3. It is seen that no recording is made with a voltage between the upper threshold voltage V_a (about +400 V) and the lower threshold voltage $-V_b$ (about -400 V) and that the recording may be effected with a suitable recording voltage higher than the upper threshold voltage V_a or lower than the lower threshold voltage V_b . When the selected output $+6V_2$ is used for the electrostatic recording voltage which is higher than the upper threshold voltage +400V, only the selected stylus makes a recording but the other styluses will not make a recording because the spurious voltage is much less than $+6V_2$. In other words, the spurious voltage is so selected as to fall in the range between the upper and lower threshold voltages V_a and, $-V_b$ whereas the selected output voltage, is selected as to be higher than the higher threshold voltage V_a or lower than the lower threshold voltage, $-V_b$.

Referring back to FIG. 1, the control unit comprising the selecting pulse signal generator 12 and the gate circuit 13 will be described hereinafter. The selecting pulse signal generator 12 is adapted to generate the pulse signals for selecting the styluses of the multistylus electrode 16. That is, the generator 12 outputs the signals corresponding to the elements of the columns 1-16 of the winding matrix shown in Table 1. In practice, however, the generator 12 outputs the signal "0" when the element is +1 and the signal "1" when the element is -1.

Flip-flops 211, 212, 213 and 214 of a binary counter 21 give the outputs a_1, a_2, a_3 , and a_4 which correspond to the elements of the second, third, fourth and fifth rows of the winding matrix shown in Table 1. The output a_5 which corresponds to the element of the sixth row of the winding matrix is obtained by $a_1 \oplus a_2 \oplus a_3 \oplus a_4$, this logic operation being performed by exclusive OR circuits 221, 222 and 223. Since the elements of the first row are all -1s, no logic circuit for giving the signal 0 is provided.

Next the mode of operation of the control unit including the driver 14 will be described hereinafter. First all of the flip-flops 211-214 of the binary counter 21 are set to the state 1, and in response to the clock pulses transmitted from a clock pulse generator 20, the output signals 1 and 0 corresponding to the elements of the columns of the winding matrix are fed into the gate circuit 13 comprising AND gates 241+~246+ and 242-~246- and NOT circuits 231-235. Only one of each pair of AND gates 242' and 242- . . . , 246+ and 246- is opened by the signal from the selecting signal generator 12. To the AND gates 241-246 are applied the picture signals in synchronism with the clock pulses and the pulses from a monostable multivibrator 25 which determines the width of pulses fed to the transformer assembly 15 through driver 14. For instance, when the output a_1 from flip-flop 211 in the signal generator 12 is 0, a pulse of which height is determined by the picture signal and of which width is determined by the pulse from the monostable multivibrator 25 is fed to an amplifier 142 in the driver 14 through the AND gate 242+. On the contrary, when the output a_1 is 1, the pulse is fed to the amplifier 142 through the AND gate 242-. The amplifiers 142-146 of the driver 14 are of the bipolar type and give the voltage signal $+V_1$ to the terminals E_2-E_6 when the pulse signal is fed from AND gates 242+~246+ and give the voltage signal $-V_1$ to

the terminals E_2-E_6 , when the pulse signal is fed from AND gates 242-~246-. The amplifier 141 gives the output signal $+V_1$ of which height is determined by the picture signal to the input terminal E_1 of the transformer assembly 15. Thus, the selected output the magnitude of which is dependent upon the magnitude of the picture signal appears at the output terminal F in the sequence determined by the winding matrix Table 1. The styluses of the multistylus electrode 16 are energized to form an electrostatic latent image upon the recording medium.

The pulse width, which is determined by the monostable multivibrator 25, must be so selected as to satisfy the following conditions:

1. the pulse width or duration must be longer than the pulse width of about 0.1μ sec. required for electrostatic recording.
2. the pulse width must be short so that the cores of the transformer assembly 15 are not saturated so as to avoid distortion of the output voltage.
3. the interference between the adjacent pulses must not distort the output voltage waveforms of the transformer assembly.

In the instant embodiment, bipolar amplifiers 141-146 are used because the bipolar output voltages must be applied to the input terminals E_1-E_6 , but they are generally complex in construction so that a transformer assembly 15' in which the positive and negative voltages can be induced across the secondary windings in response to a unipolar primary voltage may be used as will be described in detail hereinafter with reference to FIG. 4.

Referring to FIG. 4, the primary windings $H_{10}, H_{20}, H_{30}, H_{40}, H_{50}$ and H_{60} are wound on the cores T_1-T_6 , respectively, in the same direction as the primary windings in FIG. 1 whereas the primary windings $H_{11}, H_{21}, H_{31}, H_{41}, H_{51}$ and H_{61} are wound in the opposite direction. One end of each of the primaries H_{10} and H_{11} are connected together and are grounded whereas the other ends are connected to input terminals E_{10} and E_{11} , respectively. In like manner, one end of each of the primaries H_{20} and H_{21} , H_{30} and H_{31} , H_{40} and H_{41} , H_{50} and H_{51} , and H_{60} and H_{61} are connected together respectively and grounded whereas the other ends are connected to the input terminals $E_{20}, E_{21}, E_{30}, E_{31}, E_{40}, E_{41}, E_{50}, E_{51}, E_{60}$ and E_{61} , respectively. When the input voltages are applied to the input terminals $E_{10}, E_{20}, E_{30}, E_{40}, E_{50}$ and E_{60} , the output terminal F_1 is selected, that is the selected output voltage appears at the output terminal F_1 . When the input voltages are applied to the input terminals $E_{10}, E_{20}, E_{30}, E_{40}, E_{51}$ and E_{61} , the selected output voltage appears at the output terminal F_2 since the primaries H_{51} and H_{61} are wound in the direction opposite to that of the other primaries $H_{10}-H_{40}$.

Second Embodiment

In the electrostatic recording system utilizing a multistylus electrode in which fine styluses are put closely to give fine picture, the electrical insulation layer between the adjacent styluses is very thin (for example less than 0.1 mm) and the high electrostatic recording voltages (for example higher than 600V) are applied to the styluses so that the electrical insulation between the adjacent styluses tends to be frequently broken and the discharge occurs between the adjacent styluses. As a result, the quality of the recorded image becomes very poor and unsatisfactory and in some cases the styluses are severely damaged. Furthermore, it is not preferable

from an economical view point that the potential difference between the adjacent styluses becomes too high because of the increase in power consumption and also because the ineffective energy consumed due to the stray capacitance between the adjacent styluses is in proportion to the square of the potential difference between the adjacent styluses. It is therefore preferable to minimize the potential difference between the adjacent styluses by utilizing the spurious outputs of the transformer assembly. For this purpose, the winding matrix shown in Table 2 is used.

5 second embodiment is substantially similar to the first embodiment except that the transformer assembly 15 is constructed based upon the winding matrix shown in Table 2 and the selecting pulse signal generator 12 is modified to give the output signals also based upon the matrix shown in Table 2. The generator 12 gives the output signals $b_1 = a_1$, $b_2 = a_1 \oplus a_2$, $b_3 = a_2 \oplus a_3$, $b_4 = a_3 \oplus a_4$, and $b_5 = a_4$ instead of the output signals a_1 , a_2 , a_3 , a_4 , and $a_5 = a_1 \oplus a_2 \oplus a_3 \oplus a_4$.

10 Third Embodiment

In the third embodiment of the present invention, the

	F_1	F_2	F_3	F_4	F_5	F_6	F_7	F_8	F_9	F_{10}	F_{11}	F_{12}	F_{13}	F_{14}	F_{15}	F_{16}

Table 2

The winding matrix shown in Table 2 is an improvement of the winding matrix shown in Table 1. In the transformer assembly based upon the winding matrix shown in Table 2, the voltage difference between the adjacent output terminals is $4V_2$ at the most whereas the voltage difference in the transformer assembly of the first embodiment is $8V_2$.

When the elements of the two columns of the matrix shown in Table 2 are compared, it is seen that two elements are always different from each other. For example the elements of the first and second columns are different from each other in the 5th and 6th rows.

The matrix shown in Table 2 is obtained by rewriting the matrix shown in Table 1. That is, the columns of the matrix shown in Table 1 are re-arrayed in the order of the 1st, 2nd, 4th, 3rd, 7th, 8th, 6th, 5th, 13th, 14th, 16th, 15th, 10th, 12th, 11th and 9th. In summary, the columns of one winding matrix may be rewritten or re-arrayed so that the number of elements in the corresponding rows different from each other in two adjacent selected columns may be minimized. Alternatively, such a winding matrix may be formed independently and a transformer assembly may be constructed based upon this winding matrix so that the voltage difference between the adjacent output terminals may be minimized. It is a mathematical problem to obtain a winding matrix of the type described above.

Next referring to FIG. 5 illustrating diagrammatically the second embodiment of the present invention, the

25 transformer assembly has k input terminals and 2^k output terminals. When one output terminal is assigned a number j , then $j-1$ is a positive integer from 0 to $2^k - 1$ and is given in the binary system

$$j-1 = a_{1j} a_{2j} \dots a_{ij} \dots a_{kj}$$

where $a_{ij} = 1$ or 0 at the i -th digit position from the most significant digit.

30 Next from the following equations

$$\begin{cases} b_{ij} = a_{1j} \\ b_{ij} = a_{1j} \oplus a_{i-1j} \\ (i = 2, 3, \dots, k) \\ c_{ij} = -2b_{ij} + 1 \\ (i = 1, 2, \dots, k) \end{cases}$$

35 b_{ij} is calculated. The results when $k = 4$ are shown in Table 3.

40 When the transformer assembly is constructed based upon a winding matrix shown in Table 4 in which c_{ij} is an element of the i -th row and j -th column, the selected output voltage is kV_2 whereas the voltage difference between the adjacent output terminals is $2V_2$. b_{ij} is known as Gray code in which the digits of the consecutive numbers are the same in every place except one, and in that place the digits differ by one unit. c_{ij} is the code in which when b_{ij} is 0, it is replaced by +1 whereas when b_{ij} is 1, it is replaced by -1. The winding matrix shown in Table 4 is obtained by arraying the rows of the column c in Table 3 as the columns and the columns as the rows.

j	$j-1$	a				b				c			
		a_{1j}	a_{2j}	a_{3j}	a_{4j}	b_{1j}	b_{2j}	b_{3j}	b_{4j}	c_{1j}	c_{2j}	c_{3j}	c_{4j}

Table 4

Fourth Embodiment

Next, the fourth embodiment in which the transformer assembly has n input terminals and 2^k output terminals ($k = \text{positive integers less than } n$), will be described. The transformer assembly is constructed based upon the (n, k) error-correcting code so that the voltage difference between the adjacent output terminals may be minimized.

First, the simplest example where $n = 4$ and $k = 3$ will be described. In this case, the $(4,3)$ code may be utilized. When one output terminal is assigned a number j , then $(j-1)$ is a positive number from 0 to 2^k-1 which is expressed in the binary system as follows:

$$j-1 = a_{1j} a_{2j} \dots a_{kj} \quad (j = 1, 2, \dots, 2^k)$$

Since $k = 3$, the right term is $a_{1j} a_{2j} a_{3j}$. $a_{1j}, a_{2j}, a_{3j}, a_{4j} = a_{1j} \oplus a_{2j} \oplus a_{3j}$ is called $(4,3)$ code, which is shown in Table 5, column a . It is seen that any two elements are different from each other when two rows are compared with each other. In the error-correcting code, the number of digits positions in which the corresponding digits of two binary numbers of the same length are different is called a "Hamming distance" or a "distance." The minimum of distance is called the "minimum distance." In the $(4,3)$ code, the distance is greater than 2 so that the minimum distance is 2. Of the bits a_{1j}, a_{2j}, a_{3j} and a_{4j} of $(4,3)$ code, three bits a_{1j}, a_{2j} and a_{3j} in the form of binary number system are called the information bits whereas a_{4j} obtained by the calculation of the information bits is called a check bit.

j	a				b				c			
	a_{1j}	a_{2j}	a_{3j}	a_{4j}	b_{1j}	b_{2j}	b_{3j}	b_{4j}	c_{1j}	c_{2j}	c_{3j}	c_{4j}
1	0	0	0	0	0	0	0	0	1	1	1	1
2	0	0	1	1	0	0	1	1	1	1	-1	-1
3	0	1	0	1	0	1	0	1	-1	-1	1	-1
4	0	1	1	0	0	1	0	1	1	-1	-1	1
5	1	0	0	1	1	1	0	0	-1	-1	1	1
6	1	0	1	0	1	1	1	0	-1	-1	1	1
7	1	1	0	0	1	0	1	0	-1	1	-1	-1
8	1	1	1	1	1	0	0	1	-1	1	1	-1

(4,3) code shown in column b of Table 5 is used to construct a transformer assembly in which the voltage difference between the adjacent output terminals becomes minimum. The information bits b_{1j}, b_{2j} and b_{3j} corresponding to the bits a_{1j}, a_{2j} and a_{3j} are given by utilizing Gray code by

$$\begin{cases} b_{1j} = a_{1j} \\ b_{2j} = a_{2j} \oplus a_{1j} \quad (j = 1, 2, \dots, 8) \\ b_{3j} = a_{3j} \oplus a_{2j} \end{cases}$$

and

$$b_{4j} = b_{1j} \oplus b_{2j} \oplus b_{3j}$$

In the improved (4,3) code, the distance between any two adjacent code words is 2.

Next, based upon the following equation

$$C_{ij} = -2b_{ij} + 1 \quad (i = 1, 2, 3 \text{ and } 4; \text{ and } j = 1, 2, \dots, 8)$$

Os in the column b of Table 4 are replaced by 1s whereas 1s by -1s so that the code shown in column c in Table 4 is obtained. In the transfer assembly constructed based upon the code in column c , the voltage

difference between the adjacent output terminals becomes minimum.

In practice, in the transfer assembly based upon the $(4,3)$ code described above, the spurious output becomes -4, but it may be increased by ± 2 by superimposing a constant bias voltage so that the selecting ratio of 1/3 may be obtained when the selected output is 6.

So far, Gray code is used in order to improve the (n, k) code so as to have the minimum distance between adjacent code words, but it does not follow that Gray code is always used. The following codes may be utilized in the present invention.

1. A code in which the parity check is made by additional bits and which is generally represented by $(k+1, k)$ code. An example is $(4,3)$ code described hereinbefore.

2. The so-called orthogonal array code.

3. $(12,7)$ code represented by

$$\begin{aligned} b_{4j}, b_{5j}, b_{6j}, b_{7j}, b_{2j} \oplus b_{4j} \oplus b_{5j}, b_{2j} \oplus b_{6j} \oplus b_{7j}, b_{1j} \oplus b_{2j} \oplus \\ b_{4j}, b_{1j} \oplus b_{2j} \oplus b_{5j}, b_{1j} \oplus b_{3j} \oplus b_{6j}, b_{1j} \oplus b_{3j} \oplus b_{7j}, b_{3j} \oplus b_{4j} \oplus b_{5j} \end{aligned}$$

The bits b_{1j}, b_{2j} and b_{3j} are not used though they are information bits. This code is an improvement of SASAKI code. In addition, SASAKI code, Golay codes such as $(18,9)$ code, and $(24,12)$ code may be utilized.

Fifth Embodiment

In the fifth embodiment, the unipolar pulses are applied to the input terminals E_1-E_5 of the transformer assembly 15 in which two secondary windings are connected. Referring to FIG. 6, the primary windings wound on the cores T_1-T_5 in the same direction are connected to the input terminals E_1-E_5 , respectively, and four secondary windings are wound on each of the cores T_1-T_5 in the same direction. The winding matrix of this transformer assembly 15 is shown in Table 6.

	F_1	F_2	F_3	F_4	F_5	F_6	F_7	F_8	F_9	F_{10}
T_1	1	1	0	0	0	0	0	1	1	0
T_2	1	0	1	1	0	0	0	0	0	1
T_3	0	1	1	0	1	1	0	0	0	0
T_4	0	0	0	1	1	0	1	1	0	0
T_5	0	0	0	0	0	1	1	0	1	1

Table 6

In Table 6, 1 represents the secondary winding while 0 represents no secondary winding. The secondary windings of the columns are connected in series. For instance, two 1's in the first column of the winding matrix represent the secondary windings wound on the cores T_1 and T_2 are connected to the output terminal F_1 in series. The feature of the winding matrix shown in Table 6 is that when two columns are compared with each other, there are always two different elements. A further feature is that two elements of each column are always 1s whereas three elements are always 0s. Since

each column has two elements which are 1s, the matrix is a sort of fixed weight error-correcting code where the weight is 2. When the driving pulse inputs are applied to the input terminals corresponding the elements 1s of the i -th column, the selected output voltage appears at the F_i terminal, and the selected output is $2V_2$ whereas the spurious output is V_2 .

The transformer assemblies may be constructed based upon some fixed weight error-correcting codes known in the experimental designs as balanced incomplete block designs. Steiner system which is represented by $S(t, k, v)$ is known as a set of arrangements out of v objects into blocks of k objects in which the block that contains any combination of t objects is found only once. The element n_{ij} of the combination matrix representing the above arrangement is 1 when the i -th object is contained in the j -th block, but 0 when the i -th object is not contained in the j -th block. In order to construct the transformer assembly based upon this matrix, the input terminals are represented by the objects whereas the output terminals are represented by the blocks and the combination matrix is used as the winding matrix. Then, the number of input terminals equals v , the weight is k , the selecting ratio is $(t-1)/k$, and the maximum number of output terminals is vC_t/kC_k , where C is the symbol of combination.

For example, Mathieu code is $S(5,8,24)$ so that the number of input terminals is 24, the weight is 8, the selecting ratio is 4/8 and the maximum number of output terminals is 759.

The advantage of the fixed weight error-correcting code resides in the fact that the unipolar driving pulses may be used so that the driving circuit may be made simple in construction. In the transformer assembly constructed based upon the combination matrix the output terminals are selected one by one.

Sixth Embodiment

Next referring to FIG. 7, the sixth embodiment of the present invention will be described hereinafter. The facsimile receiver shown in FIG. 7 is of the type capable of recording simultaneously three picture elements. In the control unit 25, the serial picture signals applied to the input terminal 11 are converted into three parallel picture signals which are applied to amplifiers 261, 262 and 263 in the driver 26. The outputs of the amplifiers 261, 262 and 263 are applied to the input terminals E_{01} , E_{02} and E_{03} of the transformer assembly 27. In order to designate the recording positions of the first three picture signals, the recording position selecting signal is applied to the amplifier 264 so that the driving pulse or the output of the amplifier 264 may be applied to the input terminal E_{10} of the transformer assembly 27 which is constructed based upon a winding matrix shown in Table 7.

wound on the cores. The number of secondary windings may be reduced when the voltage with the same magnitude and the same polarity are induced across them. From Table 7, it is readily seen that the elements

5 of the fourth, fifth and sixth rows (T_{10} , T_{20} and T_{30}) are the same respectively in the first to third columns, in the fourth to sixth columns, and in the seventh to ninth columns, so that only one winding can be wound on each of the cores T_{10} , T_{20} and T_{30} as shown in FIG. 7. The 10 features of the winding matrix shown in Table 7 are that when two columns are compared, two elements differ and that each column has always two 1s. Since the weights of all of the rows are 2 in the matrix shown in Table 7, the matrix is a fixed weight error correcting 15 code. When the input voltages $+V_1$ are applied to the input terminals E_{01} - E_{03} and the input voltage $+V_1$ is simultaneously applied to the input terminal E_{10} , the selected output voltage $+2V_2$ is induced across the series-connected secondary windings corresponding to the 20 first, second and third rows of the winding matrix shown in Table 7, but the spurious outputs 0 or $+V_2$ appear at the other output terminals F_{21} - F_{23} and F_{31} - F_{33} . When the input voltage is applied to input terminal E_{10} (where $i=1, 2$ and 3) and to one of the input terminals 25 E_{01} , E_{02} or E_{03} , to two of them or all of them, the selected output voltage $+2V_2$ appears at one of the three output terminals F_{11} , F_{12} and F_{13} , at two of them or all of them. The selecting ratio is 1/2. As with the case of the other embodiments of the present invention, the 30 level of the spurious output is so selected that no electrostatic recording will be made.

In response to the clock pulses supplied from the clock pulse generator 28, the picture signals applied to the input terminal 11 are sequentially transferred into 35 a shift register 29, and when three picture signals are transferred into the shift register 29, a counter 30 gives the output signal to AND gates 31 so that the contents of the shift register 29 are simultaneously transferred in parallel through the gates 31 into a buffer register 32. The counter 30 also gives the output signal which has 40 been reset. As a result, a flip-flop 341 changes to the state 1 whereas other flip-flops 342 and 343, to the state 0. The output signal of the counter 30 is transmitted also to a monostable multivibrator 35 which gives 45 to AND gates 33 pulse signals with a suitable pulse duration so that the three picture signals stored in the buffer register 32 are transferred in parallel to the amplifiers 261, 262, and 263 in the driver 26, and the recording position designating signals are transferred into the driver 26 from the shift register 34. These signals are amplified and applied to the transfer assembly 27 so 50 that the selected output voltages appear at the output terminals F_{11} , F_{12} and F_{13} depending upon the picture signals. As a result, three dots are simultaneously re-

	F_{11}	F_{12}	F_{13}	F_{21}	F_{22}	F_{23}	F_{31}	F_{32}	F_{33}
T_{01}	1	0	0	1	0	0	1	0	0
T_{02}	0	1	0	0	1	0	0	1	0
T_{03}	0	0	1	0	0	1	0	0	1
T_{10}	1	1	1	0	0	0	0	0	0
T_{20}	0	0	0	1	1	1	0	0	0
T_{30}	0	0	0	0	0	0	1	1	1

Table 7

In Table 7, the element 1 represents that the secondary windings are wound on the cores T_{01} - T_{03} and T_{10} - T_{30} whereas the element 0 represents that no winding is

corded by styluses 35 on the recording medium 37.

As soon as the contents of the shift register 29 are transferred into the buffer register 32, the next three

picture signals are stored one by one in the shift register. In like manner, the next three dots are recorded. The above operations are cycled until the desired electrostatic recording is obtained.

In order to improve the selecting ratio, between the ground and the junction G_0 between the primary winding H_{30} and a common lead wire there may be inserted a primary winding wound upon a core whose secondary

may be minimized. That is, in the matrix shown in Table 8 the elements of the adjacent columns are different in only two rows. Another improvement of the matrix shown in Table 7 is shown in Table 9.

To explain this winding matrix, the output terminals are represented by F_{ij} ($i = 1, 2, \text{ and } 3; j = 1, 2, \text{ and } 3$) and arrayed in the order of $(i-1) \cdot 3 + j$, and the input terminals are represented by E_{ij} ($i = 1, 2 \text{ and } 3$) and E_{i0}

	F_{11}	F_{12}	F_{13}	F_{21}	F_{22}	F_{23}	F_{31}	F_{32}	F_{33}
E_{01}	1	0	0	0	1	0	0	0	1
E_{02}	0	1	0	0	0	1	1	0	0
E_{03}	0	0	1	1	0	0	0	1	0
E_{10}	1	1	1	0	0	0	0	0	0
E_{20}	0	0	0	1	1	1	0	0	0
E_{30}	0	0	0	0	0	0	1	1	1

Table 9

winding is inserted between the ground and the junction G_1 of the secondary windings L_{10} , L_{20} and L_{30} , so that a voltage equal to $-V_2/2$ is always induced across the secondary winding. Then, the selected output voltage becomes $+3/2 V_2$, the spurious voltage is $-1/2 V_2$ or $+1/2 V_2$, and the selecting ratio is $1/3$.

When the transformer assembly of the type shown in FIG. 7 has input terminals $E_{01}, E_{02}, \dots, E_{0m}$ and $E_{10}, E_{20}, \dots, E_{n0}$, the number of input terminals is $(m+n)$ whereas the number of output terminals is $(m \cdot n)$. The output terminals are represented by F_{ijk} ($i = 1, 2, 3, \dots, l; j = 1, 2, \dots, m; k = 1, 2, \dots, n$), and the input terminals, by E_{00k} ($k = 1, 2, \dots, n$), E_{0j0} ($j = 1, 2, \dots, m$) and E_{i00} ($i = 1, 2, \dots, l$). In the winding matrix of the transformer assembly, the elements of the column corresponding to the output terminal F_{ijk} are 1s at the rows corresponding to the input terminals E_{100}, E_{0j0} and E_{00k} whereas the remaining elements are 0s. The transformer assembly based upon this winding matrix has $(l+m+n)$ input terminals and $(l \cdot m \cdot n)$ output terminals.

Seventh Embodiment

The seventh embodiment is an improvement of the sixth embodiment so that the voltage difference between the adjacent output terminals of the transformer assembly may be minimized. The winding matrix shown in Table 7 is improved as shown in Table 8.

1	0	0	0	0	1	1	0	0
0	1	0	0	1	0	0	1	0
0	0	1	1	0	0	0	0	1
1	1	1	0	0	0	0	0	0
0	0	0	1	1	0	0	0	0
0	0	0	0	0	0	1	1	1

Table 8

The winding matrix shown in Table 8 is obtained by rearranging the columns of the matrix shown in Table 7 so that the number of elements in the corresponding rows of the adjacent columns different from each other

($i = 1, 2$ and 3). In the column F_{ij} , the elements in the rows corresponding to the input terminals E_{10} and E_{0x} (where x is given from the relation $x+i-j \equiv 1 \pmod{3}$) are 1s whereas the elements in the remaining rows are 0s. In like manner, the winding matrix shown in Table

25 8 is formed by putting $x=j$ when i is an odd number and putting $x=4-j$ when i is an even number. When i takes on the value of $1, 2, \dots, l$ and j , on the value of $1, 2, \dots, m$, the number of input terminals is $(l+m)$ and the number of output terminals, $(l \cdot m)$. When the output terminals are represented by F_{ijk} ($i = 1, 2, \dots, l; j = 1, 2, \dots, m; k = 1, 2, \dots, n$) and arrayed in the order of $((i-1) \cdot m + (j-1)) \cdot m \cdot k$. The input terminals are represented by E_{00k} ($k = 1, 2, \dots, n$), E_{0j0} ($j = 1, 2, \dots, m$) and E_{i00} ($i = 1, 2, \dots, l$). The elements of the column F_{ijk} in the rows corresponding to the input terminals E_{100}, E_{0j0} and E_{00k} are 1s whereas the elements in the other rows are 0s, where $x=j$ when i is an odd number, $x=m+1-j$ when i is an even number, $y=k$ when $(i-1) \cdot l + j$ is an odd number whereas $y=n+1-k$ when $(i-1) \cdot m + j$ is an even number.

30 35 40 Alternatively, x and y may be derived from
 $x+i-j \equiv n \pmod{m}$, and
 $y+(i-1) \cdot m+j-1 \equiv k \pmod{n}$

45 50 where h, h' are constant integers. Therefore, the number of input terminals is $(l+m+n)$ and the number of output terminals, $(l \cdot m \cdot n)$. The signal distance between the adjacent columns is minimum.

Eighth Embodiment

Next referring to FIG. 8 the eighth embodiment of a transformer assembly in accordance with the present invention will be described. The transformer assembly is constructed based upon a fixed weight error correcting code derived from element code (where $p = 2, 3, \dots$). One example, quaternary code, shown in Table 10 will be described. Since the corresponding elements of the columns differ in more than two rows, the minimum distance of this code is 2.

F_1	F_2	F_3	F_4	F_5	F_6	F_7	F_8	F_9	F_{10}	F_{11}	F_{12}	F_{13}	F_{14}	F_{15}	F_{16}
a_{1j}	0	1	2	3	1	2	3	0	2	3	0	1	3	0	1
a_{2j}	0	1	2	3	0	1	2	3	2	3	2	3	0	1	2
a_{3j}	0	0	0	1	1	1	1	2	2	2	2	3	3	3	3

Table 10

a_{3j}, a_{2j} in Table 10 is expressed in the quaternary system of $j - 1$, where column number $j = 1, 2, \dots, 16$. a_{1j} is given by

$$a_{1j} = a_{2j} \oplus a_{3j} \pmod{4}$$

a_{3j}, a_{2j} is called an information symbol whereas a_{3j} is called a check symbol. In order to construct a transformer assembly based upon the matrix shown in Table 10, 12 input terminals and 16 output terminals are provided. The output terminals are represented by F_j ($j = 1, 2, \dots, 16$) whereas the input terminals, by E_{ik} ($i = 1, 2$ and 3 ; $k = 0, 1, 2$ and 3). Instead of E_{ik} , the notation $E(i, k)$ will be used hereinafter. The elements of the column j are 1s in the three rows corresponding to the input terminals $E(1, a_{1j}), E(2, a_{2j})$ and $E(3, a_{3j})$ whereas the elements in the other rows are 0s. Thus, a winding matrix as shown in Table 11 is obtained.

terminals. The selected output voltage is $6V_2$ which corresponds to the number of groups; the spurious output is 0 or $2V_2$, and the selecting ratio is $1/3$.

In a transformer assembly constructed based upon the winding matrix except the first group, the selected output voltage is $+5V_2$ because the weight of the matrix is 5, and the selecting ratio is $2/5$. In case of a transformer assembly constructed based upon the matrix except the first and the second groups, the selected output voltage is $+4V_2$, and the selecting ratio is $1/2$. In case of a transformer assembly based upon the matrix except between the first and the third group, the selected output voltage is $+3V_2$ and the selecting ratio is $2/3$.

In like manner, a transformer assembly may be constructed based upon a binary, ternary, quinary or any other code. The advantages of the eighth embodiment

Table 11

Each row consists of three groups each consisting of 35 four elements, and the three groups are obtained from the first, second and third rows of the matrix in Table 10. The matrix shown in Table 11 is a fixed weight error correcting code.

Based upon the winding matrix shown in Table 11, the transformer assembly shown in FIG. 8 is constructed. In this transformer, secondary windings are wound on the cores at the positions corresponding to the elements 1 of the winding matrix shown in Table 11. When the input voltage $+V_1$ is applied to the input terminals corresponding to the elements 1 of one column j whereas no input voltage is applied to the input terminals corresponding to the elements 0, the selected output voltage $+3V_2$ which corresponds to the weight of the matrix appears at the output voltage F_j . The spurious output is 0 or $+V_2$, and the selecting ratio is $1/3$.

Another example of a quaternary code is shown in Table 12.

are that the selecting ratio is good and the logic circuit for generating the selecting signals is simple in construction. The output terminals of the transformer assembly are selected one by one.

Ninth Embodiment

The ninth embodiment is an improvement of the quaternary code of the eighth embodiment. The columns of the matrix shown in Table 10 are re-arrayed so that the distance between the adjacent columns may become minimum, thereby minimizing the voltage difference between the adjacent output terminals.

Since $a_{2j}a_{3j}$ gives a matrix with $l = m = 4$ as with the case of the seventh embodiment, b_{2j}, b_{3j} are obtained from the following equations:

$$b_{3j} = a_{3j}$$

$$b_{2j} = a_{2j} - a_{3j} \pmod{4}$$

and used instead of $a_{2j}a_{3j}$, b_{1j} is obtained from the following relation:

$$b_{1j} = b_{2j} + b_{3j} \pmod{4}$$

which is an equation for calculating a check symbol

Table 14

The method used in the instant embodiment may be applied to other p element codes. When the information code is represented by

$a_{1j}, a_{2j}, \dots, a_{kj}$, and

the check symbol is represented by

$a_{k+1, j}, \dots, a_{nj}$.

Then, the information symbol is obtained from the following relations:

$$b_{1j} = a_{1j}$$

$$b_{ij} = a_{1-1,j} - a_{ij} \pmod{p} \quad i = 2, 3, \dots, k.$$

The check symbols $b_{k+1,j}, \dots, b_{nj}$ are calculated by the method for deriving the check symbols from the information symbols. $b_{1j}, b_{2j}, \dots, b_{nj}$ are used instead of $a_{1j}, \dots, a_{nj}$.

For example when $p = 5$, the information symbol is $a_{1j} a_{2j} a_{3j}$ ($j = 1, 2, \dots, 125$), and the check symbols are given by

$$a_{4j} = a_{1j} + a_{2j} + 3a_{3j}$$

$$a_{5j} = a_{1j} + 2a_{2j} + 2a_{3j}$$

$$a_{6j} = a_{1j} + 4a_{2j} + a_{3j}$$

the error-correcting code with the minimum distance of 2 is obtained. From these information symbols and check symbols, the improved codes $b_{1j}, \dots, b_{nj}$ are obtained by applying the above described method.

Tenth Embodiment

A fixed weight error correcting code based upon which is constructed a transformer assembly may be obtained based upon a combinatorial theory as will be described hereinafter.

The combinations ${}_5C_2$ of selecting two digits out of five digits, 0, 1, 2, 3 and 4 are 10, that is 01, 02, 03, 04, 12, 13, 14, 23, 24 and 34. From these combinations may be formed a winding matrix for the transformer assembly as shown in Table 15.

35 40 45 50 55

nations, are in columns. That is, the matrix has five rows and 10 columns because the number of combinations is 10. The elements of each column are 1s in the rows corresponding to the digits used in the combinations whereas the other elements are zero. The matrix is fixed weight error correcting code, weight is 2, and the minimum distance is 2. The output terminals of the transformer assembly constructed based upon this matrix are selected one by one.

Next, the improvement of a transformer assembly constructed based upon the combinatorial theory will be described. A matrix shown in Table 16 is obtained by re-arranging the columns of the matrix shown in Table 15, and has the feature that the minimum distance between the adjacent columns is 2.

1	1	0	0	0	0	0	1	1	0
1	0	1	1	0	0	0	0	0	1
0	1	1	0	1	1	0	0	0	0
0	0	0	1	1	0	1	1	0	0
0	0	0	0	0	1	1	0	1	1

Table 16

That is, the order of the combinations is changed as follows:

01, 02, 12, 13, 23, 24, 34, 30, 40 and 14 in such a way that the distance may become a minimum. Based upon the matrix shown in Table 16 a winding matrix may be obtained. To change the order of combinations, one arbitrary combination called a fundamental block is selected out of the 10 combinations. The combinations in which the two digits of the fundamental block are increased one by one are arrayed in the following order:

01, 12, 23, 34, 40.

However, since the five digits 0-4 are used, they are cyclically arrayed. That is, when 4 is increased by one, it returns to 0.

Out of the combinations except the above five combinations is selected another fundamental block which is most close to the first and second combinations 01 and 12. That is, the combination 02 has only one digit different from those of the combinations 01 and 12 so that the combination 02 is selected as another fundamental block. The digits of the fundamental block 02 are cyclically increased as follows:

02, 13, 23, 30, 41.

The first and second combinations of series thus obtained are alternately arrayed as follows:

01, 02, 12, 13, 23, 24, 34, 30, 40, 41.

This series has a feature that the distance between the adjacent combinations is a minimum. From this series, the winding matrix shown in Table 12 is formed, and based upon this winding matrix, a transformer assembly is obtained in which the voltage difference between the adjacent output terminals is a minimum.

The method for forming the combinations by cyclically increasing by one the digits contained in the fundamental block is known as the difference set method.

In like manner, from each of three fundamental blocks 01, 03, and 02, seven combinations are obtained as follows:

01, 12, 23, 34, 45, 56, 60

03, 14, 25, 36, 40, 51, 62

02, 13, 24, 35, 46, 50, 61.

They are arrayed in series from the first column as follows:

01, 03, 02, 12, 14, 13, 23, 25, 24, 34,

36, 35, 45, 40, 46, 56, 51, 50, 60, 62, 61.

When the three fundamental blocks are so selected that the distances between the first four combinations are a minimum, the series of the combinations has the minimum distance.

Eleventh Embodiment

Referring to FIG. 9, the 11th embodiment of the present invention will be described. In the eleventh embodiment, the output lines of a transformer assembly are branched in a tree fashion so that a plurality of output terminals may be simultaneously selected. The secondary windings are wound on the cores T_{10} - T_{80} based upon Steiner system S (3,4,8). The secondary voltage of $+V_2$ is induced across each of the secondaries, and, in like manner, the secondary voltage $+2V_2$ is induced across each of the branched secondaries wound on the cores T_{01} and T_{02} . In the transformer assembly of the type described, out of the output terminals F_{ij} ($i=1, \dots, 14$; $j=0$ and 1) may be selected one of or both of the output terminals whose subscripts i are identical. For example, either of terminal F_{10} or F_{11} or both of F_{10} and F_{11} may be simultaneously selected. The selected output voltage is $+6V_2$, the spurious output is 0 or $+4V_2$; and the selecting ratio is 2/3. Furthermore, when, as with the case of the sixth embodiment the secondary windings for improving the selecting ratio are added, the selecting ratio may be improved to 1/2. In some cases, it is preferable to vary the secondary voltages induced across the secondary windings in practice.

In the transformer assembly constructed based upon a (n,k) code or a fixed error correcting code, the output lines may be branched in tree fashion, as in the case of the eleventh embodiment, so that a plurality of out-

put terminals may be simultaneously selected. In order to minimize the voltage difference between the adjacent output terminals, the methods described with reference to the fourth, seventh, ninth, and tenth embodiments may be applied to a transformer assembly constructed based upon a (n,k) code or a fixed weight error correcting code, and the method described with reference to the seventh embodiment may be applied to the branched portions of the secondary windings.

Twelfth Embodiment

Referring to FIG. 10, the twelfth embodiment will be described. The object of the twelfth embodiment is to reduce the spurious output. One end of each of the secondary windings L_{ii} - L_{i4} ($i=1, 2, 3$ and 4) is connected to the output terminals F_{ii} - F_{i4} whereas the other ends is connected to the intermediate terminals K_i . When the input voltage is applied to one of input terminals E_{i0} ($i=1, 2, 3$ and 4) and to one of the input terminals E_j ($j=1, 2, 3$ and 4), simultaneously, the selected output voltage $+2V_2$ appears at one of the output terminals F_{ij} . The spurious voltages 0 or V_2 appear at the other output terminals. The selecting ratio is 1/2, but in practice it is higher than 1/2 because of the stray capacitances between the secondary windings.

FIG. 11 shows the cross sections of the secondary windings wound on the bobbins of the cores T_1 - T_4 . The bobbins are also indicated by the same reference characters T_1 - T_4 , and the primary windings are not shown. In order to reduce the stray capacitance between the adjacent secondary windings, they are so wound as to be out of contact with each other as possible, and wound in one row on each core. For example, the secondary windings L_{11} and L_{21} are wound on the bobbin adjacent to each other. It is assumed that the stray capacitance between the adjacent secondary windings be C and that the stray capacitance between the secondary windings which are not adjacent to each other is so small that it is negligible.

When the secondary windings of the transformer assembly shown in FIG. 10 are wound in the order of the junctions K_1 - K_4 , the selecting ratio is degraded in some cases because of the reason to be described hereinafter. The secondaries L_{11} and L_{21} connected to the junctions K_1 and K_2 , respectively, are wound on the bobbin T_1 adjacent to each other so that there is a stray capacitance C between them. The secondaries L_{12} and L_{22} connected to the junctions K_1 and K_2 are wound on the bobbin T_2 adjacent to each other so that there is also a stray capacitance C between them. When there are four bobbins, the overall stray capacitance between the junctions K_1 and K_2 is $4C$. However, since the secondary windings connected to the junctions K_1 and K_3 are not wound adjacent to each other on the bobbins, the stray capacitance between them may be negligible or 0. The stray capacitances between the junctions K_1 - K_4 are summarized as shown in Table 17.

	K_1	K_2	K_3	K_4
60	K_1		$4C$	0
	K_2	$4C$		$4C$
	K_3	0	$4C$	
	K_4	0	0	$4C$

Table 17

For example, when the driving pulses are applied to the input terminals E_1 and E_{10} to select the output terminal F_{11} , the secondary voltage V_2 is induced across the sec-

ondary winding L_{10} , and the voltage at the junction K_1 is V_2 . However, no secondary voltage is induced across the secondary winding L_{20} so that the potential at the junction K_2 is 0 if there is no stray capacitance. However, there is a stray capacitance of $4C$ between the junctions K_1 and K_2 in practice so that the potential at the junction K_2 is inevitably increased when the impedance of the secondary winding L_{20} is high under the influence of the potential at the junction K_1 . Therefore, the voltage at the junction K_2 is added to the secondary voltage V_2 induced across the secondary winding L_{21} so that the spurious voltage appearing at the output terminal F_{21} becomes higher than V_2 and the selecting ratio becomes higher than $1/2$.

One method for solving this problem is to ground the junctions K_1 – K_4 through a suitable capacitor or resistor so that the impedance between each junction and the ground may be reduced, thereby decreasing the effect of the stray capacitance. However, this method has a defect in that the loads of the secondary windings L_{10} – L_{40} are increased so that the high current driving pulses must be supplied in order to obtain a predetermined secondary voltage.

Another method is to reduce the stray capacitance by increasing the spacing between the secondary windings, but this method has also the defects that the transformer assembly becomes large in size and that the coupling between the primary and secondary windings is degraded so that the leakage inductance is increased with the result of the distortion of the output waveform.

From Table 17 it is seen that the stray capacitance between the junctions K_1 and K_2 is $4C$ whereas the stray capacitance between the junctions K_1 and K_3 is zero. Therefore, according to the present invention, the secondary windings are so wound on the bobbin that the stray capacitance between them may be equalized. That is, the maximum stray capacitance is decreased so that the selecting ratio may be improved.

FIG. 12 shows the cross sections of the bobbins upon which are wound the secondary windings in accordance with the present invention. The stray capacitances between the secondary windings are shown in Table 18.

	K_1	K_2	K_3	K_4
K_1		$2C$	$2C$	$2C$
K_2	$2C$		$2C$	$2C$
K_3	$2C$	$2C$		$2C$
K_4	$2C$	$2C$	$2C$	

Table 18

For example, the stray capacitance between the junctions K_1 and K_2 can be reduced to $2C$ because the secondary windings connected to the junctions K_1 and K_2 are not wound adjacent to each other except the secondary windings L_{11} and L_{21} on the bobbin T_1 and the secondary windings L_{14} and L_{24} on the bobbin T_4 . The stray capacitances between the junctions K_1 – K_4 are all $2C$. That is the stray capacitance $4C$ of the arrangement shown in FIG. 11 is reduced to one half so that the selecting ratio may be improved in proportion. The overall stray capacitance is $24C$ both in Tables 17 and 18 and equals the double of the overall capacitance between adjacent secondary windings in all bobbins. This cannot be changed even when the arrangement of the

secondary windings is changed. Since the stray capacitance is completely equalized in the arrangement shown in FIG. 12, no more improvement can be attained even the arrangement of the secondary windings is varied.

Thirteenth Embodiment

The thirteenth embodiment is the generalization of the twelfth embodiment. In this embodiment, a plurality of output terminals connected to a junction or intermediate terminal through secondary windings are called a block; the number of output terminal of one block is called the size of a block M ; and the number of junctions is called a block number N . For example, in the arrangement shown in FIG. 10 $M = 4$ and $N = 4$. In general, a transformer assembly with the block size M and the block number N has $(M + N)$ input terminals and $(M \cdot N)$ output terminals, and is called a $(M \cdot N)$ transformer assembly.

It is assumed that $M = P - 1$ and $N = P$ or $P - 1$ where P is a prime number. When $M =$

$P - 1$ and $N = P$, the secondary winding wound on the m -th core ($m = 1, 2, \dots, M$) of the k -th block ($k = 0, 1, \dots, N-1$) is represented by L_{km} . The secondary winding L_{km} is wound at the i -th position $i=0, 1, \dots, P-1$ to be given by the following equation (1) so as to equalize the stray capacitance.

$$i \equiv k m \pmod{P} \quad (1)$$

30 This is the congruence equation and $\pmod{P}$ represents congruent modulo 5. Since i , k and m are elements of a residue class (modulo P) field, the following relation is held:

$$i = k m \quad (2)$$

40 It is assumed that there may be a stray capacitance between the adjacent secondary winding but there may be no stray capacitance between the secondary windings which are not adjacent to each other. Furthermore, in order to simplify the calculation there may be a stray 45 capacitance between the 0-th secondary winding and the last or $(N-1)$ th secondary winding and that where $a(i, j)$ denotes a stray capacitance between the secondary windings at the i th position and the j th position on a core.

$$50 a(0, N-1) = a(N-1, 0) = C \quad (3)$$

55 Since $a(i, j)$ is dependent upon $|i - j|$,

$$a(i, j) = a(i - j, 0) \quad (4)$$

60 Since $a(i - j, 0)$ is a function of $i - j$, $a(i, j)$ is rewritten in the form of

$$65 a(i, j) = a(i - j, 0) - a(i - j) \quad (5)$$

If the stray capacitance between the junctions K_k and K_l is b_{kl} , then

23

$$\begin{aligned}
 b_{kl} &= \sum_{m=1}^M a(i, j) = \sum_{m=1}^M a(i-j) \\
 &= \sum_{m=1}^M a(km-lm) \\
 &= \sum_{m=1}^M a((k-l)m)
 \end{aligned}
 \quad (6)$$

Therefore,

$$b_{kl} = 0 \text{ (when } k = l)$$

$$b_{kl} = \sum_{m=1}^M a(i) = 2C \text{ (when } k \neq l)$$

the stray capacitance between the junctions is constant independently of k and l and completely equalized when $k \neq l$. If we eliminate the assumption (3) and put

$$a(0, P-1) = a(P-1, 0) = 0 \quad (10)$$

then the stray capacitance between the junctions is given by

$$b_{kl} = \begin{cases} 0 & \text{when } k = l \\ C & \text{when } k = 0 \text{ and } l \neq 0 \text{ and} \\ & \text{when } k \neq 0 \text{ and } l = 0 \\ 2C & \text{when } k \neq l, k \neq 0 \text{ and } l \neq 0 \end{cases}$$

The solution when $M = P - 1$ and $N = P$ is obtained by eliminating the 0th block and under the condition of

$$a(0, 1) = a(1, 0).$$

The result is

$$b_{kl} = \begin{cases} 0 & \text{when } k = l \\ 2C & \text{when } k \neq l \end{cases}$$

The stray capacitances are all equalized. In the conventional secondary winding arrangement, the maximum stray capacitance between the junction was $m \cdot C$ so that the greater M becomes the more remarkably the advantage of the present invention is pronounced.

So far the arrangement of the secondary windings have been described as being made in accordance with Eq. (2), but the above described method is also applied when

$$i = k/m \quad (11)$$

where i , k , and m are elements of a residue class (modulo P) field. Since $k = m$, the secondary windings are arranged as shown in the multiplication table. For example, Table 19 shows the multiplication table where $P = 5$.

i	0	1	2	3	4
m	1	0	1	2	3
1	0	1	2	3	4
2	0	2	4	1	3
3	0	3	1	4	2
4	0	4	3	2	1

Table 19

24

When $N = P$ or $P - 1$ and $M < P - 1$, the arrangement is the same with that when $M = P - 1$ is used, but since the number of bobbins is less than $P - 1$, the number of column in the arrangement is reduced accordingly so that the optimum stray capacitance equalization may be obtained.

Next, when $N = P$ and $M \geq P$, the optimum arrangement may be obtained from repetition of the arrangement for $M = P - 1$ when M is an integer multiple of $P - 1$. But when M is not an integer multiple of $(P - 1)$, the optimum arrangement may be obtained by eliminating some from the repetition of the arrangement for $M = P - 1$.

When $M = N = P$, the power series of 2 in residue class modulo P is formed. For example when $P = 5$,

$$2^0, 2^1, 2^2, 2^3$$

which are 1, 2, 4 and 3 which in turn are obtained by re-arranging the series of 1, 2, ..., $P - 1$. 2 is called a primitive root. From the above series is added with 0 to form the first series

$$1, 2, 4, 3, 0.$$

The pairs of adjacent digits are 1, 2; 2, 4; 4, 3; and 3, 0 and the four rows of Table 19 are so cyclically changed so that these digits of each pair of digits may be positioned in the first and fifth columns, respectively. That is, 0, 1, 2, 3, 4 of the first row of Table 19 is so cycled that 1 and 2 are positioned at both ends. The result is the series of 2, 3, 4, 0, 1. For the third series, the second row 0, 2, 4, 1, 3 is so cycled from the series of 4, 1, 3,

0, 2 so as to move 0, 2 to the ends. For the fourth series, the series 0, 4, 3, 2, 1 of the fourth row is so cycled as to form the series of 3, 2, 1, 0, 4 to move 0, 4 to the ends. In like manner, the fifth series becomes 3, 1, 4, 2, 0. Thus, the five rows of Table 20 are obtained. The

chance that a pair of digit come in adjacent position in a row is two at the most in an arrangement.

When P is less than 20, 2 is a primitive root when $P = 5, 11, 13$ and 19 . Therefore, the first row is

$$2^0, 2^1, 2^2, \dots, 2^{P-2}, 0$$

and the second to P -th rows may be formed in a manner substantially similar to that described hereinbefore.

P is not a primitive root when $P = 7$ and 17 , but from the first row

$$2^0, 2^1, \dots, 2^{P-3/2}, 0, 3 \cdot 2^{P-3/2}, \dots, 3 \cdot 2^1, 3 \cdot 2^0$$

the succeeding rows may be formed in a manner substantially similar to that described hereinbefore.

Next, when $M = N = P + 1$, the first and second rows are formed by adding P to the head and end of the above series, respectively. The third to $(P+1)$ -th rows may be formed by cyclically changing the series obtained by adding P 's to the heads of the second to P -th rows of the above series in such a manner that the pairs of adjacent digits of the first row are brought to both heads and ends of the rows. Table 21 shows the arrangement formed from Table 20 by the above method when $N = 6$.

2	2	2	3	4	0	1
3	4	1	3	0	2	
4	3	2	1	0	4	
5	3	1	4	2	0	

Table 20

Next, the arrangement for completely equalizing the stray capacitance for N is obtained. From this arrange-

ment, a complete arrangement developed for $2N$ may be formed. Out of $(1, 2, \dots, 2N)$, $(1, 2, \dots, N)$ are represented by alphabet whereas $(N+1, N+2, \dots, 2N)$ by alphabets with a prime such as $a', b', c', \dots$. When a row is $(a b c d \dots l)$ for N , two rows $a, b, c, d \dots l, l', \dots, d', c', b', a'$ and $l', \dots, d, c', b, a', b', c, d', \dots, l$ are obtained for $2N$. In the latter series or row, the alphabets with primes appear alternately. Thus, the arrangement for $2N$ is obtained. An example of this arrangement for $N = 10$ developed from the arrangement for $N = 5$ shown in Table 20 is shown in Table 22.

1	5	1	2	4	3	0
2	1	2	4	3	0	5

Table 22

Next, a transformer assembly with $N = 10$ composite number, that is not a prime number will be described hereinafter. When N is a prime, the $(N-1)$ rows are formed from Eq. (11) and the multiplication table of $K = im$ in such a manner that the chance that the adjacent digit pair are same is two at the most. This method may be also applied when N is a composite number. When k, i and m are elements of residue classes (modulo N) (and are called a ring in mathematics) and m and N are relatively prime, then

$$k = im \quad (12)$$

From the multiplication table of Eq. (12), the arrangement similar to those described hereinbefore may be formed. Since m and N must be relatively prime, $\phi(N)$ arrangements are possible, where $\phi(N)$ is Euler's function which gives the number of those residue classes which contain only numbers relatively prime to N .

An example when $N = 9$ is shown in Table 23.

i	0	1	2	3	4	5	6	7	8
m	0	1	2	3	4	5	6	7	8
1	0	1	2	3	4	5	6	7	8

8	2	5	3	6	0	7	1	4

Table 24

$\phi(9) = 6$ arrangements are obtained. Table 24 shows nine arrangements by cyclically changing the arrangements shown in Table 23 and adding further three rows. Even when the stray capacitances between the junctions cannot be completely equalized by the methods described hereinbefore, the arrangements are determined by the method of the instant embodiment. If the stray capacitance between the junctions are calculated from

$$b_{kl} = \sum_{m=1}^M a(i, j),$$

where $i = f(l, m)$ and $j = f(k, m)$,

it is seen that the maximum stray capacitance is remarkably reduced from that of the arrangement in which the secondary windings are arranged in the order of the number of junctions. $f(k, m)$ is a function representing that the secondary winding L_{km} of the k th block is placed at the i th position in the m th bobbin. For example, the maximum stray capacitance may be reduced less than $1/2$ so that the selecting ratio may be remarkably improved. When the complete equalization of b_{kl} is not obtained, some modifications are required. Furthermore, the stray capacitance may be considerably equalized even when the positions of the secondary windings are selected from the random number.

So far the secondary windings have been described as being wound in one layer on the bobbin, but they may be wound in more than two layers. This will be described with a reference to a $(M \cdot N)$ transformer assembly with $M = 8$ and $N = 9$. FIG. 13 shows the cross section of the bobbin on which are wound the secondary windings in three layer and in three column. The layers are designated by i_1 ($i_1 = 0, 1$ and 2) and the columns, by i_2 ($i_2 = 0, 1$ and 2). Furthermore, the position of the secondary winding is indicated by $i = 3i_1 + i_2$ ($i = 0, 1, 2, \dots, 8$). In like manner based upon Eqs. (2) - (9) the method for calculating the stray capacitance between the junctions will be described. The arrangement of the windings is defined by

$$i = k m$$

where, opposed to Eq. (2), i, k and m are elements in the Galois field $GF(3^2)$, and m represent eight elements except 0 of $GF(3^2)$. In order to represent the elements of the Galois field, the following polynomial representations are used.

$$\begin{aligned} i_1 x + i_2 \\ k_1 x + k_2 \quad (k_1 = 0, 1 \text{ and } 2; k_2 = 0, 1 \text{ and } 2) \\ m_1 x + m_2 \quad (m_1 = 0, 1 \text{ and } 2; m_2 = 0, 1 \text{ and } 2 \text{ except } m_1 = m_2 = 0) \end{aligned}$$

The correspondence between k ($k = 0, 1, 2, \dots, 8$) and m ($m = 1, 2, \dots, 8$) is given by

$$\begin{aligned} k &= 3k_1 + k_2 \\ m &= 3m_1 + m_2 \end{aligned}$$

The multiplication table of $i = km$ represented by the polynomial representation of Galois field is shown in Table 25. (In tabulating the multiplication table, i_1, i_2, k_1, k_2, m_1 and m_2 are considered as elements of residue classes modulo 3; x^2 is substituted by $2x + 1$; and then the formula of multiplication of ordinary polynomial equations may be applied).

k	0	1	2	3	4	5	6	7	8	
m	$kx+k_2$	0	1	2	x	$x+1$	$x+2$	$2x$	$2x+1$	$2x+2$

8 3 1	2 7 8	4 6 2	5 2 8
4 2 6	1 6 5	8 1 3	7 4 1

Table 26

The arrangement of the secondary windings based upon this multiplication table is shown in Table 26. The stray capacitance between the i th position and the j th position is represented by $a(i,j)$, and since i and j are represented by two digits i_1 and i_2 ; and j_1 and j_2 , respectively, $a(i,j)$ is rewritten in the form of $a(i_1, i_2; j_1, j_2)$. It is assumed that there may be a stray capacitance C_1 between the adjacent positions in the row and there may be the stray capacitance C_2 between the adjacent positions in the column. For the simplification of the calculation, it is assumed that there may be the stray capacitances between the ends of the rows and columns. As with the case of Eq. (3)

$$a(i_1, 0; i_1, 2) = a(i_1, 2; i_1, 0) = C_1 \quad (i_1 = 0, 1, 2) \quad (14)$$

$$a(0, i_2; 2, i_2) = a(2, i_2; 0, i_2) = C_2 \quad (i_2 = 0, 1, 2) \quad (15)$$

Then

$$a(i_1, i_2; j_1, j_2) = a(i_1 - j_1, i_2 - j_2; 0, 0) \quad (16)$$

It is assumed that i and j are elements of Galois field, then

$$a(i, j) = a(1 - j, 0) \quad (17)$$

and Eq. (17) may be rewritten in the form of

$$a(i, j) = a(1 - j) \quad (18)$$

The stray capacitance b_{kl} between the junctions K_k and K_l is given, as with the case of Eqs. (5) – (9), by

$$b_{kl} = \sum_{m=1}^{\infty} a(i, j) = \sum_{m=1}^{\infty} a(i - j) = \sum_{m=1}^{\infty} a(km - lm)$$

$$= \sum_{m=1}^{\infty} a[(k - l)m]$$

$$= 0 \quad (\text{when } k = l)$$

$$= \sum_{m=1}^{\infty} a(i) = 2C_1 + 2C_2 \quad (\text{when } k \neq l)$$

Therefore, the stray capacitance may be completely equalized. When the assumptions Eqs. (13) and (14) are not made and the stray capacitance $C_1 = C_2 = C$ exists only between the adjacent secondary windings, the complete equalization cannot be attained, but the maximum stray capacitance may be reduced to one half as compared with the case where the secondary windings are arranged in the order of the number of junctions K so that the selecting ratio may be improved.

The method described above is also applied when $N = P^2$ (where P is prime) and the secondary windings are arranged in P layer and P columns. Another example of the arrangement obtained from $GF(5^2)$ is shown in Table 27.

Table 27

The above method is also applied when $N = P^2 - 1$, which is the case where the secondary winding with $K = 0$ is eliminated.

In this case, i , k and m are assumed to be the elements of Galois field $GF(P^2)$, and the arrangement of secondary windings is determined from

$$i = k m$$

When the bobbin has three grooves, as shown in FIG. 14, in which the secondary windings are wound in three layer and in three column, the stray capacitance between the grooves may be disregarded. Therefore, the winding arrangement may be obtained from the multiplication table of Galois $GF(3^3)$. This method may be applied when $N = P^3$ or $N = P^3 - 1$.

When the bobbin has $N_1, N_2, \dots, N_n$ grooves in which are wound the secondary windings L_n ($n = 1, 2, 3, \dots$) in one and if the stray capacitance between the grooves is negligible, each column of the arrangements in one layer described hereinbefore may be placed in each groove. An example of the arrangement when the bobbin has four grooves and there are 25 secondary windings is shown in Table 28.

5 This table is obtained from the arrangement for $M = P - 1$, $N = P$ where $P = 13$, developing it for $2N$.

In the instant embodiment, the voltage at the junction has been described as being varied by the output of the transformer, but it will be understood that the 40 voltage at the junction or intermediate terminal may be varied by using other means such as transistors.

45 As described hereinbefore, according to the instant embodiment of the present invention, the secondary windings are positioned based upon the combinatorial theory so that the stray capacitance between the secondary windings may be distributed and the stray capacitance between the junctions or intermediate terminals may be almost completely equalized. As a result, the selecting ratio may be remarkably improved.

50 Fourteenth Embodiment

Next referring to FIG. 16, the fourteenth embodiment in which a transformer assembly is incorporated in a character drum electrostatic printer will be described. Character code signals are applied to the input terminal 11 and transferred into a buffer memory 41. When the character code signals for one line on a recording medium are stored in the buffer storage 41, they are immediately transferred into a print storage 42.

65 Characters on a character drum 49 are displaced every three columns as shown in FIG. 16. The length of one character on the character drum 49 is W . The characters in the first, second and third columns from the left are displaced with respect to those in the fourth, fifth and sixth columns by $W/20$. In like manner, all the characters are displaced by $W/20$ every three columns. Upon rotation of the drum 49, the characters A are aligned with back electrodes P_{011}, P_{012} and P_{013} ; then P_{021}, P_{022} and P_{023} ; P_{031}, P_{032} and P_{033} ; $\dots$; P_{201}, P_{202} and P_{203} . When the drum 49 is further rotated

through an angle corresponding to $W/20$, the characters B are aligned with the back electrodes P_{011} , P_{012} , and P_{013} ; . . . , P_{201} , P_{202} , and P_{203} . In like manner, other characters are aligned with the back electrodes sequentially. A transformer assembly 46 used in the electrostatic printer of the type described is of the type described with reference to the sixth or eleventh embodiment. In the instant embodiment, the transformer assembly is of the type described with reference to the 10 6th embodiment, and has 60 output terminals F_{011} – F_{203} three of which are simultaneously selected.

A character counter disk 47 around which are disposed the codes representing the positions of the characters and a pickup 48 detect the characters and the back electrodes aligned with the characters and transmit the character code to a comparator 43 which compares the character code with the character code signals stored in the print storage 42. When they coincide with each other, a recording signal is transmitted to a 15 transformer assembly control circuit 45, and in response to the output signal thereof the selected output voltage is induced across a selected secondary winding and applied to the corresponding back electrode. A recording medium 50 is transported between the character drum 49 and the back electrodes, and the electrostatic recording is made upon the recording medium by the selected back electrodes.

The electrostatic printer of the type described can record three characters in parallel. Because of the electrostatic recording, the recording time is short (for example 20 μ sec.). The recording speed is therefore equal to or faster than that of a mechanical line printer. The electrostatic printer has an advantage that no noise is produced because of nonimpact recording.

Next, the driving circuit of the electrostatic printer of the type described is compared with that of a mechanical line printer capable of printing 60 letters per line. The mechanical printer requires 60 driving circuits whereas the electrostatic printer requires only 23 driving circuits. For the sake of explanation, the cores T_{01} , T_{02} and T_{03} are combined with the cores T_{010} , T_{020} , . . . , and T_{200} in the instant embodiment, but when the cores T_{01} – T_{06} are combined with the cores T_{010} , T_{020} , . . . , and T_{100} , the number of driving circuits may be reduced to 17.

The driving circuits of the electrostatic printer are simple in construction as compared with those of the mechanical line printer because the power consumption is less.

The advantages of the electrostatic recording apparatus of the present invention described in detail hereinbefore may be summarized as follows:

The supply of electrostatic recording voltage to a stylus is accomplished electrically, so that the recording speed is remarkably increased.

Since a large number of styluses are supplied with electrostatic recording voltage from a small number of driving inputs, the number of driving circuits and cores of the transformer assembly may be reduced so that an electrostatic recording apparatus which is simple in mechanism, light in weight and inexpensive to manufacture may be provided.

Since the low voltage driving input is converted into a high electrostatic recording voltage by the transformer assembly, the driving circuits may comprise low-voltage transistors so that an electrostatic record-

ing apparatus simple in mechanism may be provided at a low cost.

We claim:

1. An electrostatic recording apparatus comprising a transformer assembly comprising
  - a plurality of cores equal in number to a length of code words of a predetermined error correcting code,
  - a plurality of primary windings wound on said plurality of cores, respectively, and
  - a plurality of selecting lines the number of which is equal to the number of the code words of said error correcting code at most and each of which comprises a plurality of series-connected secondary windings wound on said cores, respectively, in accordance with the elements of each of the code words of said error correcting code;
  - means for energizing said plurality of primary windings with a set of energizing current for selecting a desired one of said selecting lines, each current that composes said set of energizing currents corresponding to each of the elements of the code word associated with said desired selecting line so that the secondary voltages of a predetermined magnitude may be induced across said secondary windings, thereby inducing a selected output voltage across said selected selecting line while inducing across the remaining selecting lines spurious output voltages, respectively, which are lower than said selected output voltage by a magnitude in proportion to a distance between the code word associated with said selected line and each code word associated with each remaining selecting lines;
  - means for generating a set of signals in response to the input information so that the generated set of signals may be amplified to produce said set of energizing currents which may be applied to said primary windings of said transformer assembly to induce said selected output voltage across said selected selecting line; and
  - means for forming electrostatic images, impressing said selected output voltage upon a plurality of electrodes connected to said selecting lines, on a recording medium located in contact with said electrodes, the magnitude of said selected output voltage being so chosen that the input information may be recorded upon said electrostatic recording medium by the discharge between said medium and said selected electrode upon which is impressed said selected output voltage while said spurious output voltage may make no recording due to the threshold characteristics of the discharge between said recording medium and the remaining electrodes upon which said spurious output voltages are impressed.
2. An electrostatic recording apparatus as defined in claim 1 wherein said transformer assembly comprises a plurality of cores equal in number to a length of the code words of a predetermined (n, k) error correcting code, where n denotes the length of the code words and k , an integer not larger than n , a plurality of primary windings, each being wound on each of said n cores, and
  - a plurality of selecting lines the number of which is equal to 2^k at most and each of which comprises a plurality of secondary windings connected in series equal in number to the length of said code words

n and wound on said n cores, respectively, in the directions in accordance with each element of each code word of said (n, k) error correcting code; said means for energizing said primary windings energizes each primary winding with the respective driving currents, whose polarity is depending upon each element of a selected code word of said (n, k) error correcting code so that the secondary voltages of the polarities dependent upon the polarity of said driving current and the direction of said secondary winding coupled to said primary winding may be induced, the secondary voltages of one polarity being induced across the n secondary windings of the selected selecting line associated with said selected code word of said (n, k) error correcting code so that the n secondary voltages may add up to the selected output voltage on said selected selecting line, the spurious output voltage induced across each of the remaining selecting lines being $n-2d$ secondary voltages which consists of $n-d$ secondary voltages in the one polarity and d secondary voltages of the opposite polarity, where d denotes the distance between said selected code word and the code word associated with each of the remaining selecting line by cancelling partly one another.

3. An electrostatic recording apparatus as defined in claim 1 wherein said transformer assembly comprises a plurality of cores equal in number to a length of the code words of a predetermined (n, k) error correcting code, where n denotes the length of the code words and k , an integer not larger than n , a plurality of primary windings, every two of which are wound on each of said cores in directions opposite to each other, a plurality of selecting lines the number of which is 2^k at most and each of which comprises a plurality of secondary windings connected in series equal in number to the length of said code words n , and wound on said n cores, respectively, in the directions in accordance with each elements of each code word of said (n, k) error correcting code; and said means for energizing primary windings energizes each one of said two primary windings on each of said n cores in accordance with each element of a selected code word of said (n, k) error correcting code so that the secondary voltages of the polarities depending upon the direction of said energized primary windings and the direction of said secondary windings coupled to said primary windings may be induced, the secondary voltages of one polarity being induced across the n secondary windings of the selected selecting line associated with said selected code word of said (n, k) error correcting code so that the n secondary voltages may add up to the selected output voltage on said selected selecting line, the spurious output voltage induced across each of the remaining selecting lines being $n-2d$ secondary voltages which consists of $n-d$ secondary voltages in the one polarity and d secondary voltages of the opposite polarity, where d denotes the distance between said selected code word and the code word associated with each of the remaining selecting line, by cancelling partly one another.
4. An electrostatic recording apparatus as defined in claim 3 wherein said transformer assembly comprises a plurality of cores equal in number to a length n of the code words of a predetermined Gray code,

a plurality of primary windings, a plurality of selecting lines the number of which is 2^n at most and each of which comprises a plurality of secondary windings wound on said cores in the directions in accordance with the elements of each code word of said Gray code in which the distance between the adjacent code words is minimum, whereby the number of cores on which the direction of the secondary windings are opposite for any two adjacent selecting lines may be made minimum with the result that the number of secondary voltages of the opposite polarities induced across the adjacent selecting lines may be minimized and that the difference between the output voltages of the adjacent selecting lines may be minimized to be $2d'$ secondary voltages, where d' denotes the minimum distance.

5. An electrostatic recording apparatus as defined in claim 3 wherein said transformer assembly comprises a plurality of cores equal in number to a length n of the code words of a predetermined (n, k) error correcting code, when k denotes an integer less than n ,

a plurality of primary windings; and a plurality of selecting lines the number of which is equal to 2^k at most and each of which comprises the secondary windings wound on said n cores, respectively, in the directions in accordance with the elements of each code word of said (n, k) error correcting code; the distance between the adjacent code words of said (n, k) error correcting code being minimized using Gray code for the information digits of the code words, whereby the number of cores on which the directions of the secondary windings are opposite for any two adjacent selecting lines may be made minimum with the result that the number of secondary voltages of the opposite polarities induced across the adjacent selecting lines may be minimized and that the difference between the output voltages of the adjacent selecting lines may be minimized to be $2d'$ secondary voltages, where d' denotes the minimum distance, by cancelling partly one another.

6. An electrostatic recording apparatus as defined in claim 1 wherein said transformer assembly comprises a plurality of cores equal in number to a length of the code words of a predetermined fixed weight error correcting code,

a plurality of primary windings equal in number to said cores, each of said primary windings being wound on each of said cores, and a plurality of selecting lines each of which comprises a plurality of secondary windings equal in number to the weight w of said fixed weight error correcting code, connected in series, each of said secondary windings being wound on the cores corresponding to the element "1" of each of said code words consisting of the combination of the elements "1" and "0," the secondary voltages of the same polarity being induced across said secondary windings; and

said means for energizing the primary windings energizes w of the primary windings wound on the cores corresponding to the elements "1s" of the selected code word of said fixed weight error correcting code associated with the selected selecting line so that the secondary voltages may be induced across

the secondary windings which are coupled through cores to said w energized primary windings, the secondary voltage being induced across each of the w series-connected secondary windings of said selected selecting line so that the w secondary voltages may add up to the selected output voltage on said selecting line while the spurious output voltage induced across each of the remaining selecting lines being $(w-d/2)$ secondary voltages, where d denotes the distance between said selected code word and the code word associated with each of the remaining selecting lines.

7. An electrostatic recording apparatus as defined in claim 6 wherein said transformer assembly comprises a plurality of cores equal in number to a length of the code words of a predetermined fixed weight error correcting code in which the distance between the adjacent code words is minimum,

a plurality of primary windings,

a plurality of selecting lines each of which comprises a plurality of secondary windings wound on said cores, respectively, in accordance with each code word of said fixed error correcting code, whereby the number of the secondary windings of the adjacent selecting lines wound on the same core may become maximum and the difference between the output voltages of the adjacent selecting lines may be $d'/2$ secondary voltages, where d' denotes the minimum distance, which is the minimum difference among the output voltages.

8. An electrostatic recording apparatus as defined in claim 6 wherein said transformer assembly comprises a plurality of cores equal in number to a length of a fixed weight error correcting code derived from a predetermined p -element error correcting code, where p denotes a positive integer larger than one, the code words of said fixed weight error correcting code being equal in number to those of said p -element error correcting code and the length of said fixed weight error correcting code being $m \times p$ where m denotes the length of said p -element error correcting code, said cores being arranged as to consist of m groups of p cores;

a plurality of primary windings, each being wound on each of said cores, and

a plurality of selecting lines equal in number to the number of the code words of said fixed weight error correcting code and each of which comprises a plurality of secondary windings connected in series and equal in number to m the number of said groups of cores, each of said secondary windings being wound on said cores in accordance with said fixed weight error correcting code in such a way that the i th (where $i=1, 2, 3, \dots, m$) secondary winding of said selecting line is wound on the h th core in the i -th group of cores, where h denotes the i th element of the code word of said p -element error correcting code corresponding to said selecting line; and

said means for energizing the primary windings with a set of driving currents for selecting one of said selecting lines, energizes each selected one of said primary windings in each of m groups corresponding to each of the m elements of the code word of said p -element error correcting code associated with said selected selecting line, so that the secondary voltages may be induced across the secondary

windings coupled to said m selected primary windings, the secondary voltage being induced across each of the m series-connected secondary windings of said selected selecting line so that the m secondary voltages may add up to selected output voltage on said selecting line while the spurious output voltage induced across each of the remaining selecting lines being $(m-d/2)$ secondary voltages, where d denotes the distance between the code words of said fixed weight error correcting code associated with said selected selecting line and associated with each of the remaining selecting lines.

9. An electrostatic recording apparatus as defined in claim 8, wherein said transformer assembly comprises a plurality of cores equal in number to a length of a fixed weight error correcting code derived from a predetermined p -element error correcting code in which the distance between the adjacent code words is minimum

a plurality of primary windings, and

a plurality of selecting lines, each of which comprises a plurality of secondary windings wound on said cores, respectively, in accordance with each code word of said fixed weight error correcting code, whereby the number of the secondary windings of the adjacent selecting lines wound on the same core may be made maximum and the difference between the output voltages of the adjacent selecting lines, may be $d'/2$ secondary voltages, where d' denotes the minimum distance, which is the minimum difference among the output voltages.

10. An electrostatic recording apparatus comprising a transformer assembly comprising

a plurality cores the number of which is denoted as m ,

a plurality of primary windings, equal in number to said cores, wound on said m cores, respectively, a plurality of intermediate terminals the number of which is denoted as n , and

a plurality of selecting lines the number of which is $m \times n$ and each of which comprises one of a plurality of secondary windings each n of which are wound on one of said m cores, one end of the n secondary windings wound on one common core being connected to different one of said n intermediate terminals, respectively,

means for impressing voltage upon said intermediate terminals in response to a set of selecting signals, means for energizing said primary windings of said transformer assembly with a set of current in response to said set of selecting signals, thereby inducing the secondary voltages across the secondary windings coupled through the cores to each of said energized primary windings, so that the selected output voltage consisting of the sum of the voltage impressed on said intermediate terminals and said secondary voltages induced across the secondary windings may be impressed across selected selecting lines which are conducted to the intermediate terminals impressed by said voltage and have the secondary windings that are coupled to said energized primary windings and that the spurious output voltage equal in magnitude to the voltage impressed on intermediate terminals may be impressed to the remaining selecting lines connected to said intermediate terminals impressed by said voltage while the spurious output voltage equal in

magnitude to said secondary voltages may be impressed to the remaining selecting lines coupled to said energized primary windings, said both spurious voltages being lower than said selected output voltage,

means for forming electrostatic images, impressing said selected output voltage upon a plurality of electrodes connected to said selecting lines on a recording medium located in contact with said electrodes the magnitude of said selected output voltage being so chosen that the recording may be made by the electrodes upon which said selected output voltages are impressed while not recording may be made by the electrodes upon which said spurious outputs are impressed because of the threshold characteristics of the discharge between said electrodes and said recording medium, means for storing input information signals, generating, in response to said information signals, said set of signals to select desired selecting lines in timing desired so that the recording of the input information may be made at one time for the electrodes connected to the selecting lines, across all of which one of an intermediate terminal voltage and a secondary voltage induced by an energized primary winding is impressed commonly, on said medium.

11. An electrostatic recording apparatus as defined in claim 10 wherein said means for impressing voltage upon said intermediate terminals comprises a second transformer assembly comprising

a plurality of cores equal in number to a length of code words of a predetermined error correcting code, a plurality of primary windings each wound on each of said plurality of cores, and a plurality of selecting lines equal in number to said n intermediate terminals, each of said plurality of selecting lines comprising a plurality of series-connected secondary windings wound on said cores, respectively, in accordance with the elements of each of the code words of said error correcting code, one end of each of said plurality of selecting lines being connected to each of said intermediate terminals, respectively, while the other end is connected to a common junction; and means for energizing said plurality of primary windings with a set of energizing currents in response to said set of selecting signals.

12. An electrostatic recording apparatus as defined in claim 10 wherein said means for impressing voltage upon said intermediate terminals comprises

a transformer assembly comprising a plurality of cores equal in number to said intermediate terminals n , a plurality of primary windings wound on said n cores, respectively, and

a plurality of secondary windings wound on said n cores, respectively, one end of said secondary windings being connected to said intermediate terminal, respectively, the other ends being connected to a common junction; and

means for energizing one of said primary windings in response to said set of selecting signals.

13. An electrostatic recording apparatus as defined in claim 10 wherein said secondary windings of said transformer assembly connected to the adjacent electrodes and connected to adjacent intermediate termi-

nals are wound on the same core, so that the difference between the output voltages of the adjacent electrodes may become minimum which is equal to the voltage impressed upon the intermediate terminals at the most.

5 14. An electrostatic recording apparatus as defined in claim 13 wherein the i th selecting line ($j = 1, 2, \dots, m$) of the selecting lines connected to the odd-numbered intermediate terminals has one of the secondary windings wound on the j th core in said transformer assembly, and the j th selecting line ($j = 1, 2, \dots, m$) of the selecting lines connected to the even-numbered intermediate terminals has one of the secondary windings on the $(m - j + 1)$ th core in said transformer assembly.

15 15. An electrostatic recording apparatus as defined in claim 15 wherein the j -selecting line ($j = 1$ through m) of selecting lines connected to the i th intermediate terminal ($i = 1$ through n) has one of the secondary windings on the x th core in said transformer assembly, where x is given by $x + i + j = k$ (modulo m) where k is a constant integer.

20 16. An electrostatic recording apparatus as defined in claim 10 wherein said n secondary windings connected to said n intermediate terminals in each of said m cores are arranged in accordance with predetermined m arrays of n digits which are so arranged that the chance that a pair of digits come into the adjacent position in said m arrays is not larger by one than the mean number of the chance that a pair of digits come into the adjacent position in said m arrays for all the combinations $nC2$ of pairs of n digits, whereby the chance that the secondary windings connected to a pair of said intermediate terminals come to the adjacent position on the same core may be equalized with the result that the maximum stray capacitance between a pair of said intermediate terminals may be reduced.

25 17. An electrostatic recording apparatus as defined in claim 16 wherein said secondary windings are wound in a plurality of layers.

30 18. An electrostatic recording apparatus comprising a rotary character drum provided with a plurality of circumferentially arranged character-shaped electrodes, the arrays of said electrodes constituting a plurality of rings of characters, each of which comprises a series of characters provided for each column of printed page, each m of said rings of characters constituting n groups, where m and n are integers, the disposition of characters in different groups of rings being displaced in the circumference direction of said drum;

35 an electrostatic recording medium disposed tangentially relative to said drum;

a plurality of back electrodes equal in number to said rings of characters, said back electrodes being disposed to cooperate with one of said rings of characters, in an array on said electrostatic recording medium, each of said back electrodes corresponding to each of said columns, each m of said back electrodes constituting n groups corresponding to said groups of rings of characters, upon rotation of said drum said back electrodes being aligned one group over each of said characters in groups of rings;

40 means to rotate said drum at a constant angular velocity;

45 a character counter for detecting the characters in group on said drum over which are aligned said

back electrodes and generating character position signals;
 a transformer assembly comprising
 a plurality of cores equal in number to the number of rings of characters in a group m ,
 a plurality of primary windings wound on said cores, respectively,
 a plurality of intermediate terminals equal in number to the number of groups of rings of characters n , each of which corresponds to said group of back electrodes,
 a plurality of selecting lines the number of which is $m \times n$ and each of which comprises one of a plurality of secondary windings each n of which are wound on one of said m cores, one end of the n secondary windings wound on one common core being connected to different one of said n intermediate terminals, respectively, the other end being connected to each of back electrodes in the group which corresponds to the intermediate terminal to which the selecting line is connected, and
 means for impressing a group selecting voltage upon said intermediate terminals in response to a set of selecting signals for selecting a desired electrode group; and
 an electronic control circuit comprising
 a print storage for storing therein character code sig-

nals for recording input information, a comparator for generating a set of recording signals when said character position signals coincide with said character code signals, and
 a transformer assembly control circuit to make said set of selecting signals in response to said set of recording signals, and energizing said primary windings and simultaneously making a group selecting voltage of said transformer assembly according to said set of selecting signals, so that the selected output voltage consisting of the sum of the voltage impressed on said intermediate terminals and secondary voltages induced across the secondary windings, coupled through the cores to each of said energized primary windings may be impressed across selected lines while the spurious output voltages may be impressed across other selecting lines, the magnitude of selected output voltage being so chosen that the recording may be made by the back electrodes upon which said selected output voltages are impressed while no recording may be made by the back electrodes upon which said spurious outputs are impressed because of the threshold characteristics of the discharge between said character-shaped electrode on said drum and said recording medium.

UNITED STATES PATENT OFFICE
CERTIFICATE OF CORRECTION

Patent No. 3,871,003 Dated March 11, 1975

Inventor(s) Mamoru Kondo, et al

It is certified that error appears in the above-identified patent and that said Letters Patent are hereby corrected as shown below:

Column 4, line 51: Change "asembly" to --assembly--.

Column 6, line 7: Change "pciture" to --picture--.

line 15: Change "pusle" to --pulse--.

line 66: Change "ins" to --in--.

Column 7, line 25: Change "assmebly" to --assembly--.

Column 8, line 32: Change "a_{is}" to --a_{ij}--.

Column 9, line 4: Change "30" to -- +1 --.

above line 45: Add -- Table 5 --.

Column 13, line 36: Change "E_{Oj0}" to --E_{Ojo}--.

Column 14, line 3: Change "Anothr" to --Another--.

line 8: Change "E_{Oj} (i = 1" to --E_{Oj} (j = 1 --.

line 32: Change "m·k" to --n·k--.

line 39: Change "l+j" to --m+j--.

line 42: Change "n(mod.m)" to --h(mod.m)--.

UNITED STATES PATENT OFFICE
CERTIFICATE OF CORRECTION

Patent No. 3,871,003 Dated March 11, 1975

Inventor(s) Mamoru Kondo, et al

It is certified that error appears in the above-identified patent and that said Letters Patent are hereby corrected as shown below:

Column 14, line 43: Change "k(mod.n)" to --h(mod.n)--.

line 55: Change "fromp" to -- from p --.

Column 19, line 13: Change "23" to --24--.

Column 21, line 24: Change "be" to --by--.

Column 22, line 24: Change "i = 0" to --(i = 0 --

line 25: Change "p-1" to -- p-1) --.

line 33: Change "modulu" to --modulo--.

before line 55: Insert --where a (i,j) denotes
stray capacitance between the secondary windings of the
i-th position and the j-th position on a core.--.

line 62: Change "a(i-j,0)-a(i-j)" to
-- a(i-j,0) = a(i-j) --.

Column 23, line 30: Change "P-is" to -- P-1 is --.

Column 24, line 44: Change " $2^{P-3/2}$, 0,3· $2^{P-3/2}$ " to
-- $2^{(P-3)/2}$, 0,3· $2^{(P-3)/2}$ --.

UNITED STATES PATENT OFFICE
CERTIFICATE OF CORRECTION

Patent No. 3,871,003 Dated March 11, 1975

Inventor(s) Mamoru Kondo, et al

It is certified that error appears in the above-identified patent and that said Letters Patent are hereby corrected as shown below:

Column 24, line 47: After "m" add -- = --.

Column 26, line 24: Change "f(1,m) and j = f(k,m)" to
--f(k,m) and j = f(1,m)--.

lines 46 and 48: Change " + " to -- = --.

Column 27, line 57: Change "tj" to -- j --.

Column 29, line 54: After "one" add --row--.

Column 30, line 68: Change "P₀₀₁₁" to -- P₀₁₁ --.

Column 32, line 32: Before "line" insert --selecting--.

Column 33, line 25: After "line" insert a comma.

Column 34, line 42: Cancel "line,".

line 43: Cancel the line in its entirety.

line 59: Cancel the line and substitute -- ments

"1" and "0", the secondary voltages of the --.

Column 36, line 19: After "minimum" add -- , --.

UNITED STATES PATENT OFFICE
